UNITED STATES PATENT OFFICE.

HENRY C. URBANER, OF NAPERVILLE, ILLINOIS.

HAND-PRESS FOR SHAFTING.

1,351,358.

Specification of Letters Patent. Patented Aug. 31, 1920.

Application filed December 13, 1919. Serial No. 344,757.

To all whom it may concern:

Be it known that I, HENRY C. URBANER, a citizen of the United States, residing at Naperville, in the county of DuPage, State 5 of Illinois, have invented a new and useful Hand-Press for Shafting; and I do hereby declare the following to be a full, clear, and exact description of the invention, such as will enable others skilled in the art to which 10 it appertains to make and use the same.

The invention relates to hand presses and has for its object to provide a hand press particularly adapted for use in automobile repair shops, blacksmith shops and the like 15 so that a piece of shafting may be straightened easily and quickly by applying pressure to the particular bend at a proper radial direction to the center of the shafting. Also to provide means for supporting the 20 shafting so that the same may be easily rotated and the bend ascertained and marked.

A further object is to provide a hand press for shafting wherein the frame is built up and formed from a single piece of channel iron bent upon itself so as to form a substantially U-shaped frame, the flanges of the channel extending outwardly and being provided with notches, in which notches the shaft supporting devices are held. Also to 25 brace the upper end of the U-shaped frame by means of a transversely disposed bar integral with the side members of said frame.

A further object is to provide a downwardly movable shaft straightening screw 30 which is moved downwardly through the medium of gears operated by a rotatable hand wheel.

A further object is to provide a pair of bars having bolts extending through registering elongated slots through the ends thereof adapted to coöperate with the notches in the outwardly extending flanges of the vertical portions of the frame, said elongated slots and bolts being so positioned 40 that the bars may be forced upwardly at one end so as to clear the bolt at that end from the notches and then lowered so that the cleared bolt will enter the notches below and adjacent the notches that the bolt has 45 cleared. The elongated slots allow the bars, when one end thereof has been lowered, to be forced into the opposite direction so that the bolt in the notches of the other vertical portion of the frame, may be cleared from its notches and lowered to the adjacent 50 notches so that the bars may be supported

in horizontal position or if so desired worked farther down. Also to provide bolt and notch supporting means for the bars, said notches being so constructed that they 60 will force the bolts outwardly in elongated slots in the bars so that the bars may be worked upwardly as desired.

With the above and other objects in view the invention resides in the combination and 65 arrangement of parts as hereinafter set forth, shown in the drawings, described and claimed, it being understood that changes in the precise embodiment of the invention may be made within the scope of what is 70 claimed without departing from the spirit of the invention.

In the drawings:—

Figure 1 is a front elevation of the press.

Fig. 2 is a sectional view taken on line 75 2—2 of Fig. 1.

Fig. 3 is a perspective view of a U-shaped channel iron frame.

Fig. 4 is a perspective view of the shaft holding blocks, showing the same resting 80 on the adjustable bars, which are adjusted upwardly and downwardly as desired.

Fig. 5 is a detail view showing a truing up device for supporting a shaft to ascertain the particular point of bend therein. 85

Fig. 6 is a front view of the truing up device.

Fig. 7 is a detail view showing the block supporting bars moved upwardly at one end to force one bolt out of the flange notches 90 and to cause a transverse movement of the bars so that as the freed ends of the bars are lowered, the bolt will enter the adjacent notch below.

Fig. 8 is a view similar to Fig. 7, but 95 showing the bolt after it has entered the adjacent notch below.

Fig. 9 is a view similar to Fig. 8 but showing the other ends of the bars after the bars have been manually forced toward that end and the bolt clear from the notches and the bars started downwardly toward the adjacent notches for supporting said bars in a horizontal position. 100

Referring to the drawings, the numeral 1 105 designates a U-shaped frame and 2 the upright portions thereof, which portions are in parallel relation to each other. The U-shaped frame is formed from channel iron and so formed that its flanges will be outwardly disposed. The upper end of the U-shaped frame 1 is bent at 3 and 4 so as

to form the arching portion 5, however, it has been found that by bending the channel iron as at 5, the material is stretched and is partially fractured, therefore to overcome this difficulty a transversely disposed bar 6 is provided. The ends of the bar 6 are welded to the frame at the bending points 3, thereby building up these points which have become weakened, bracing the frame 10 transversely and at the same time forming an integral brace. Secured to the lower ends of the vertical members 2 are angle irons 7 which form a base for the machine as a whole, said angle irons having their ends secured together by brace rods 8 so as to form a firm base for the machine as a whole. The flanges 9 of the vertically disposed portions 2, of the frame are provided with registering inclined notches 10, said notches 15 and the flanges of each portion 2 being at the same height from the base and forming means for supporting bars 11 and 12 in a horizontal plane. The horizontal bar 11 is supported in notches 10 by means of bolts 20 25 13, said bolts being disposed in elongated slots 13^a, so that by manipulating the bar 11 said bar may be worked upwardly or downwardly to notches at various heights from the ground. The horizontal bar 11 has 30 slidably mounted thereon brackets provided with center points 14 for supporting a shaft during a truing operation, when said shaft is provided with center depressions in its ends, thereby supporting the shaft so that it 35 may be rotated and the particular point of bend ascertained and marked. However, where the shaft is not provided with centers at its ends so that it can be supported by the centering points 14, the shaft is placed upon 40 the rotatable wheels 17 as indicated at 18 in Figs. 5 and 6 and rotated thereon so that the point of bend may be ascertained and marked. Bars 12 are supported in a horizontal position by means of bolts 19 which pass 45 through elongated apertures 19^a in the ends of said bars, and through the registering notches 10, which extend downwardly and inwardly from the outer edges of the flanges 9. When it is desired to lower the bars 12 50 which bars are of considerable weight, it will be seen by referring to Figs. 7, 8 and 9, that as the ends *a* of the bars are forced upwardly that the bolt 19 at said end will be forced into the outer end of the elongated apertures 19^a and the bars 12 also moved 55 laterally. The end *a* having been raised, said end is lowered to the position shown in Fig. 8 and the bolt 19 disposed in the inclined notches 10 adjacent the notches 10, from 60 which it has just been removed. The bars 12 after having been placed in the positions shown in Fig. 8 are then forced to one side in the direction of the arrow *b* so that the bolt 19 at said other side may be moved out 65 of engagement with the notches 10, and that

end of the bars lowered as shown in Figs. 9. It may be seen by referring to Fig. 9 that the end *c* of the bars may be lowered so that said bars will be in a horizontal plane, or if so desired may be further lowered, so that 70 the bars may be worked to a horizontal plane in any of the notches. When it is desired to raise the bars, the operation is substantially reversed to the operation set forth above. 75

Disposed on the bars 12 is a removable plate 20, on which plate V-shaped notched blocks 21 are placed, in the notches of which the shaft 18 is disposed with its particular point of bend centrally disposed between the 80 blocks 21, in which position it will be engaged by the straightening element 22 carried by a vertically disposed threaded shaft 23, said shaft 23 being slidably mounted in a bearing 24 of the bracket 25 and in a bearing 26 of the bar 6. Threaded on the shaft 23 and disposed between the bracket 25 and the bar 6 is a gear 27, which gear is a beveled one, and when rotated will thread upwardly and downwardly on the threaded 85 shaft 23 so as to move engaging element 22 into engagement with the shaft carried by the blocks 20, so that said shaft may be bent in such a manner as to remove bends therefrom. Meshing with the gear 27 is a beveled gear 28, which beveled gear is secured on a shaft 29, said shaft being rotatably mounted in a bearing of the bracket 25 and in a bearing 90 of the frame 1. The other end of the shaft 29 has secured thereto a wheel 30 100 which is adapted to be grasped by the hand of the operator for rotating the beveled gear 27, so that the bending element 22 will be moved downwardly or upwardly as desired.

The upper end of the threaded shaft 23 is 105 provided with a transversely disposed pin 31. The ends of said pin being slidably mounted in vertically disposed slots 31^a, so as to insure the vertical movement of the shaft 23 and also to limit the downward 110 movement of said shaft. However, it has been found in machines of this type where a collar or pin is used for limiting the downward movement of the threaded shaft, that said pin or collar will be sheared off 115 unless the operator is extremely careful. To overcome this difficulty a spring supported pivoted lever 32 is provided, which lever has one of its arms extending inwardly so as to be disposed in one of slots 31^a, so that the 120 end of the pin 31 on its downward movement will cause the other end of the lever which is disposed within a bell to be moved against the action of the spring 34 and can 125 pass the engaged end of the lever 32, so that an alarm will be sounded warning the operator that the machine has reached the end of its stroke.

It is to be understood that the use of the press is not limited to the straightening of 130

shafts and that bushings may be forced from castings by placing the castings on the supporting bars 12, therefore the great range of vertical adjustability of the bars 12, it being necessary at times in garages to put extremely large castings on the supporting bars for forcing various bushings from the same.

The invention having been set forth what is claimed as new and useful is:—

1. A press for straightening shafts and the like said press comprising a U-shaped frame formed from channel iron, the flanges of said channel iron being outwardly disposed, the sides of said U-shaped frame having their flanges provided with inwardly and downwardly extending notches in registration with each other and in registration horizontally to each other, said notches forming means for supporting a shaft supporting bed, a vertically movable shaft adapted to be moved downwardly into engagement with a shaft on the shaft supporting means, and means for moving said vertically disposed shaft upwardly or downwardly as desired.

2. A press for straightening shafts and the like, said press comprising a U-shaped frame formed from channel iron, the flanges of said channel iron being outwardly disposed, the vertical side arms of said U-shaped frame having their flanges provided with inwardly and downwardly extending notches in registration with each other and in registration horizontally with each other, said notches forming means for supporting a shaft supporting bed, a vertically movable threaded screw slidable in bearings of the upper end of the frame, said screw forming a bending element adapted to be forced into engagement with the shaft, gear means for moving said shaft upwardly and downwardly as desired and manually operated means in connection with said gears for rotating the same.

3. A press for straightening shafts and the like, said press comprising a U-shaped frame formed from channel iron, the flanges of said channel iron being outwardly disposed, the vertical side arms of said U-shaped frame having their flanges provided with inwardly and downwardly extending notches in registration with each other, said notches forming means for supporting a shaft supporting bed, a vertically movable threaded screw slidable in vertically alined bearings, the upper bearing being in a transversely disposed integral brace extending between the upper bending points of the sides of the frame, the other vertical bearing being carried by a bracket carried by the transverse brace, a bevel gear threaded on the threaded shaft, a bevel gear meshing with said bevel gear and carried by a horizontally disposed shaft

and means at the outer end of said horizontally disposed shaft for imparting revoluble movement to the gears and moving the threaded shaft downwardly or upwardly as desired.

4. A press for straightening shafts and the like, said press comprising a U-shaped frame formed from channel iron, the flanges of said channel iron being outwardly disposed, the vertical side arms of said U-shaped frame having their flanges provided with inwardly and downwardly extending notches in registration with each other, said notches forming means for supporting a shaft supporting bed, a vertically movable threaded screw slidable in vertically alined bearings, the upper bearing being in a transversely disposed integral brace extending between the upper bending points of the sides of the frame, the other vertical bearing being carried by a bracket carried by the transverse brace, a bevel gear threaded on the threaded shaft, a bevel gear meshing with said bevel gear and carried by a horizontally disposed shaft, means connected to said horizontally disposed shaft for rotating the same, and alarm means coöoperating with the vertically disposed threaded shaft for warning the operator that the vertically threaded shaft is approaching its limit of downward movement.

5. In combination with a press frame, said frame having vertical parallel members, a series of notches in said members, said notches inclining downwardly and inwardly, of an article supporting bed, said bed being provided with elongated apertures at its ends, transversely disposed bolts passing through said apertures and adapted to be received by the frame notches for supporting the bed, said elongated apertures and bolts being so positioned so that the bed may be worked upwardly or downwardly to various positions.

6. In combination with a press frame, having vertical parallel members, a series of notches in said members, said notches extending downwardly and inwardly, of a supporting bed, said bed being provided with elongated apertures at its ends, transversely disposed bolts passing through said apertures and adapted to be received by the frame notches for supporting the bed, said elongated apertures being of sufficient length to allow the bolt at one end of the bed to clear its notch when said end is forced upwardly and to allow said bolt when its end is lowered to enter the adjacent notch below and the bed forced longitudinally so that the bolt at the other end thereof will be allowed to clear so that its end of the bed may be lowered to the adjacent notch below or to the second notch below.

7. In combination with a press frame having vertical parallel members, said members

being formed of channel iron having their flanges extending outwardly, registering apertures in the flanges extending downwardly and inwardly, of a supporting bed, said bed comprising a pair of bars, one of said bars being on one side of the frame and the other on the other side, elongated apertures in the ends of the bars and in registration with each other, transversely disposed bolts 10 passing through the registering apertures at the ends of the bars, said bolts being adapted to be received by the flange notches, said elongated apertures being of such a

length as to allow the bed plates to be worked upwardly or downwardly to various 15 horizontal positions and supported by the bolts being disposed within the registering notches of the flanges.

In testimony whereof I have signed my name to this specification in the presence of 20 two subscribing witnesses.
